LOCK HAVING A SLIDING BOLT

Marcel Fresard, Geneva, Switzerland, assignor to Mefina S. A., Fribourg, Switzerland, a Swiss company

Application May 14, 1953, Serial No. 354,996

Claims priority, application Switzerland May 20, 1952

3 Claims. (Cl. 70—462)

The present invention has for its subject a lock of the type comprising a bolt of the type adapted to be driven by a cylinder device actuated by a key and in which the lock bolt is adapted to be moved in translation by means of a catch pivotally mounted in the lock case and provided with a pin passing through an opening of the lock bolt, said pin being adapted to be actuated by an intermediate driving member for controlling the movements of translation of the lock bolt.

The lock according to the invention is characterised in that said intermediate driving member is mounted in an adjustable manner on the end of the cylinder opposite to the keyhole, the said cylinder end and said member having the one, at least a male part and the other at least a female part of such shape that they permit of rendering angularly fixed one to the other of the two parts in four different positions, in such a manner as to allow the mounting of the lock in at least four different positions located rectangularly one relatively to another, while retaining for the key the most correct position of operation considered to be the most favourable.

In general, the normal position of the key, considered to be the most favourable, is that in which the plane of symmetry of the key is vertical.

One form of construction of the lock according to the invention is shown by way of example in the accompanying drawings, wherein:

Fig. 1 is a view of the bolt and of the intermediate driving member, the lock being assumed mounted on a door turning on a hinge with a vertical axis, located to the right of the lock.

Fig. 2 is a partial section of the lock on the line II—II of Fig. 1.

Figure 3 is a view in section along line III—III of Figure 2.

Fig. 4 is a view similar to that in Fig. 1, in which the lock is assumed to be mounted on a door pivoting on a hinge with a vertical axis, placed to the left of the lock.

Figs. 5 and 6 show diagrammatically the position occupied by the lock bolt and the intermediate driving member in the retracted and projected position of the bolt, when this is mounted on a door pivoting about a horizontal axis, the lock being secured at the top and near the left hand end of the door.

Figs. 7 and 8 are diagrammatic views similar to the previously briefly described embodiments in the case and in which the lock is mounted at the top and near the right hand end of the door.

This lock comprises a bolt formed by a lock case 1 in which is capable of sliding a lock bolt 2. The lock bolt 2 is adapted to be moved in translation by a catch 3 (see Figs. 1 and 2) pivotally mounted on a tubular part 4 formed integral with the lock case 1. A spring 5 is adapted to hold the catch 3 in the two retracted and projected positions of the bolt. The bolt is adapted to be moved by an intermediate driving member 6 partaking in the rotation of a cylinder device 7 controlled by the key 8.

2

The cylinder device 7 has not been shown in detail as it may be of any known type.

In the form of construction shown, the intermediate driving member 6 is arranged in an adjustable manner on the cylinder device 7 and is capable of occupying four different angular positions relatively to the cylinder 7.

In fact, the end of the cylinder 7 carrying the member 6 has two female parts 9 with which are adapted to engage four male parts or projections 10 of the driving member 6. In this form of construction the cylinder 7 has a bore 11 of general rectangular shape (Fig. 3) which passes through it longitudinally from one end to the other and which is adapted to serve as a seating for the key 8. A transverse groove 12 (Fig. 3) is provided at the end of the cylinder 7 to extend orthogonally relatively to the major axis of the cross-section of the bore 11. Thus the female parts 9 are formed on the one hand by the seating or bore 11 and on the other hand by the transverse groove 12. Thus the driving member 6 may be located selectively in one of four different positions at the end of the cylinder 7, said four positions being located along two axes which intersect at right angles.

The intermediate driving member 6 also has two oppositely located projections 13 adapted to co-operate with a projection 14 of the catch 3. The projection 14 passes through an opening 15 of the bolt 2. As shown particularly in Fig. 1, the opening 15 is located at the centre of the bolt and has a recess 16 extending toward one of the narrow edges of the bolt. It is also to be noted that the two end portions of the bolt 2 located on opposite sides of the opening 15 are symmetrical. It is thus possible to place the bolt selectively in one of two positions located at 180° relatively to one another in the lock case 1, this being for the purpose of making it possible to place the bolt in the closed position by turning the key either in a clockwise direction or in the reverse direction.

As shown in Fig. 2, the cylinder device is secured to a plate 17 forming a closing flange for the lock case 1 and the various parts of the lock are held together by a screw 18 screwing into a threaded hole 19 of the case 1. Other holes 20 are provided in the case 1 and in the flange 17 so as to enable the lock to be secured to a door or drawer by means of screws or bolts.

A lock as above described may be mounted selectively in one of four different positions while retaining the key in a position of operation considered to be the most favourable.

In fact, in Fig. 1 the lock is assumed to be mounted on a door pivoting about a vertical axis located to the right of the lock. This is shown in the closed position. The driving member 6 is in such a position that it suffices to turn the key through one revolution in a clockwise direction so that the projection 13 co-operates with the projection 14, after an idle rotation through half a turn, and turning the catch 3 and consequently moving the lock bolt 2 towards the right.

In Fig. 4, the lock is assumed to be mounted on a hinge with a vertical axis located at the left of the lock. The lock is shown with the bolt in projected position. It is to be observed that this position corresponds to the retracted position of the bolt shown in Fig. 1. The mounting of the lock according to Figs. 1 and 4 is thus effected without changing the position of the member 6 relative to the cylinder 7.

In Figs. 5 and 6, the lock is assumed to be mounted on a door pivoting about a horizontal axis, the lock being fixed at the top and near the left hand end of the door. In this case the casing of the lock has been turned from its positions of Fig. 1 or 4 through a quarter of a turn relative to the flange 17 on which the cylinder 7 is mounted. However, the member 6 has been moved

through a quarter of a revolution relative to the cylinder 7. Thus the key normally retains the same position as that which it occupies in the case of Figs. 1 and 4.

It is also to be noted that the threaded hole 19 and the screw 18 enable the assembly of the various parts of the lock to be maintained both in the relative positions which they occupy in Figs. 1 and 4 and in the position which they occupy in Figs. 5 and 6.

In Figs. 7 and 8, the lock is assumed to be mounted on a door pivoting about a horizontal axis, the lock being secured near the top and to the right hand end of the door. In this case it is preferred to project the bolt of the lock by turning the key in a clockwise direction as in the case of the mounting shown in Fig. 4. In the latter case illustrated, the casing 1 of the lock occupies, relative to the flange 17, the same position as that shown in Figs. 5 and 6. On the contrary the member 6 has been turned through 180° relative to the cylinder 7. Further, the bolt 2 has pivoted through 180° relative to the lock casing 1 so that the notch 16 instead of being on the right hand portion of the bolt as shown in Figs. 5 and 6, is located on its left hand portion. Thus, when the bolt of the lock is in the retracted position shown in Fig. 7 and it is to be brought into the closed position, the key is first turned through half a turn idly in a clockwise direction so as to bring the upper projection 13 into contact with the projection 14. By turning the key through another half a turn, the catch 3 is moved by the member 6, this movement of the catch thus producing an upward movement, that is to say into the closed position, of the lock bolt 2.

Various modifications in construction may be made in the lock described. Thus instead of the member 6 being capable of occupying selectively one of four different angular positions relatively to the cylinder, these two parts may be so arranged that the member 6 can only occupy selectively one of two different positions located angularly 180° apart.

I claim:

1. A lock adapted to be driven positively both in opening and in closing, comprising, in combination, a casing member, said casing member having side wall portions and top and bottom wall portions, each of said side wall portions having an opening therethrough, each opening being opposite to the opening in the side wall portion opposite to its side wall portion, a bolt member slidably mounted within said casing for movement through the respective side wall portion, at said opening thereof, said bolt member having symmetrically shaped end portions, said bolt member having an opening extending therethrough transversely of the plane in which said bolt slides, said opening being in the central portion of said bolt and having a recessed portion, the sides of said recessed portion extending toward the respective end portions of the bolt, catch means for sliding said bolt into its retracted and projected positions with respect to said casing, means for pivotally mounting said catch means between the inner surface of said top wall portion of the casing and the top surface of said bolt member, said catch means including a projection extending through

said opening of said bolt member, a cylinder having a rectangularly shaped bore extending longitudinally therethrough, whereby a key may be seated therein, said cylinder being rotatably mounted with respect to said casing at the bottom wall surface thereof transversely of the plane in which said bolt slides and having at least its end portion positioned within said casing, said end portion of said cylinder having transverse grooves extending perpendicularly with respect to the major axis of said rectangularly shaped bore, a driving means for engaging said catch means at said projection thereof extending through said bolt member opening and for causing said bolt to slide into its retracted or projected position, said driving means being positioned between the bottom surface of said bolt member and the end portion of said cylinder, said driving means including a first plurality of angularly spaced projection means for engaging said projection of said catch means and positioned in a plane transversely of said catch means projection and a second plurality of angularly spaced projection means for selectively engaging the cylinder end portion at opposite portions of said longitudinally positioned bore therethrough and the said transverse grooves, whereby said driving means may be selectively secured to said cylinder for rotation therewith and whereby the lock may be mounted on any one of a plurality of doors to be opened in at least four different directions without changing the position of the key to be inserted in the cylinder for opening and closing the door.

2. The lock of claim 1 including spring means for holding said catch means in its respective positions corresponding to the retracted and projected positions of the bolt, said spring means being positioned between the top surface of said bolt and the inner surface of said top wall portion of the casing.

3. The lock of claim 1 wherein said first plurality of said angularly spaced projection means of said driving means includes angularly movable projections spaced 180° from each other and said second plurality of angularly spaced projection means includes lug members spaced 90° from each other.
